JOHN S. HICKMAN, OF TITUSVILLE, FLORIDA.

ELECTRIC SWITCH.

1,245,103.

Specification of Letters Patent.

Patented Oct. 30, 1917.

Application filed December 29, 1916. Serial No. 139,637.

To all whom it may concern:

Be it known that I, JOHN S. HICKMAN, a citizen of the United States, residing at Titusville, in the county of Brevard and 5 State of Florida, have invented new and useful Improvements in Electric Switches, of which the following is a specification.

This invention relates to electric switches, and more especially to those wherein certain parts are movable longitudinally; and the object of the same is to produce a switch in which the terminals are completely enclosed in sockets within slideable bars of insulation material, the bars being moved 10 by a pivoted lever which may also be used as a switch for another circuit, all as hereinafter described and claimed and as shown in the drawings wherein—

Figure 1 is a plan view of this switch 20 complete, partly broken away through a pair of registering sockets.

Fig. 2 is a cross section on about the line 2—2 of Fig. 1.

In the drawings, the numeral 1 designates 25 a base of stone, porcelain, glass, or other suitable insulating material, and whereon all the mechanism of the switch is mounted as usual in devices of this character. Carried by and rising from this base are two 30 pairs of springs 2 and 3 of double right-angular formation as best seen in Fig. 2, one arm of said springs being secured flat on the face of the base and the other arm disposed above the same and projecting 35 toward the corresponding arm of the opposite spring. Within the space or channel between the bodies of these springs is disposed a pair of bars 4, 5 of insulating material, preferably fiber, which rest and slide 40 upon the face of the base and are held beneath the tips of said springs with their inner edges or faces in contact with each other so that they may slide relatively. Transversely through these bars are formed 45 holes or sockets, and in the present embodiment of my invention there is one such socket through the bar 4 and three through the bar 5, but this will depend upon the use to which the invention is to be put. By 50 preference I insert a tube 6 within each socket, and this tube should be of good insulating material, such as glass if the bars are of fiber, although the bars may be made of glass or porcelain and in that case it is 55 possible the tubes could be omitted. The tube when used forms a lining for the

socket and well may be considered as the wall thereof. Within each socket is disposed a plunger 7 preferably having at its inner end a head 8 of globular formation, 60 and a spring 9 bears this plunger inward so as to normally project its head beyond the inner face of the bar.

As the preferred use to which this switch may be put, I have shown wires connected 65 with the plungers of the several sockets. The wire lettered P may well lead to the spark plug of an internal combustion engine, and those lettered H, B and L lead respectively from the high tension circuit, 70 the battery and coil or vibrator and the low tension circuit of the sparking system. If so, then when the heads of the plungers stand in contact as in Fig. 1, there is a direct circuit from the battery through the two 75 contacting terminals and along the wire P to the plug, and the plungers connected with the wires H and L are cut out of circuit. While any suitable mechanism may be employed for moving the bars, I prefer 80 that next to be described.

The numeral 10 designates a switch lever pivoted at 11 on the base and having an ebonite handle 12 at its free end, and in the present illustration the numeral 13 designates 85 a T-head at the inner or pivoted end of the lever and fast thereon, each arm of the T being connected by a link 14 with one of the bars as shown. When now the handle of the lever is moved from side to 90 side, it will be clear that the T-head 13 thereof turns on the pivot 11 and one link 14 is drawn on while the other link 14 is pushed on, and the result is that the one bar 4 is moved to the left while the other 95 bar 5 is moved to the right, both bars sliding under the tips of the springs 2, 3. The base will be provided with a suitable guide over which the lever moves, and the guide or the base may be inscribed with words 100 or signs to indicate which circuit is closed when the lever stands in any of its several possible positions. The extremities of each link are pivoted respectively to the T-head 13 and the end of one bar, but as the latter 105 is of insulating material it is impossible for any current to get into the links and therefore into the handle. Overlying the said bar and underlying the tips of the springs I may use a cover plate 16 as best seen in 110 Fig. 2, and if this is employed it will be clear that the globular heads 8 of the sev-

eral plungers are fully inclosed and entirely surrounded by insulating material. Therefore if a spark should occur at the time a circuit is closed or broken, it is impossible 5 for it to do any injury.

Another feature of my invention consists in employing the swinging lever itself for closing another circuit—perhaps a circuit which needs to be closed when the wire P 10 is thrown respectively into communication or connection with the wires H, B or L. In the present illustration I have shown a ground wire G leading to the pivotal point 11 of the handle or lever 10, another ground 15 wire *bg* as leading from a point 17 at the midlength of the guide 18, and another wire *lg* as leading from a point 19 at one end of said guide. When the device is used on the circuit above suggested, the wire G will be 20 the main ground wire, the wire *bg* will be the ground wire for the battery, and the wire *lg* will be the ground wire for the low tension circuit. It will be obvious that when the lever stands at the midlength of the 25 guide 18 and the plug wire P is connected with the battery wire B, the battery ground wire *bg* will be connected through the lever 10 with the main ground wire G and the circuit will be complete. The same is true 30 when the plug wire is connected with the low tension wire L, its ground circuit being closed at that time. Attention is invited to the fact that this closing of the circuit or wires connected with the lever, its pivot, 35 and its guide, is entirely separate from the closing of the circuit brought about by the longitudinal reciprocation of the bars 4 and 5, and quite remote therefrom. As a result, the wires P, H, B and L may be connected 40 up in such manner that they carry a heavy or perhaps dangerous circuit whereas the other and less protected wires which are near the hands of the operator may be connected up to a lighter circuit. However, 45 as the wiring forms no part of the present invention I abstain from giving further examples. While the wires are shown diagrammatically herein as overlying the base 1, it will be clear that, as usual in switches, 50 the wires are thoroughly insulated and are laid in grooves on the under side of the base and led up through holes in it to their terminals, while the base-plate is mounted on a suitable support in a manner not necessary 55 to bring out in detail. The handle 12 may

be at either side or at the top or bottom of the base plate, and the guide may be provided with notches, serrations, or frictional means for holding the handle in any of its set positions.

What is claimed as new is:—

1. In electric switch, the combination with a base, and parallel guides thereon; of a pair of bars slidably mounted on the base between said guides and in contact with each other, one bar having a plurality of transverse sockets and the other a single socket, an insulated lining for each socket, terminals mounted in said sockets and each having a ball at its inner end and its outer end connected with one of the wires which the switch is to control, and means for longitudinally adjusting the bars simultaneously and oppositely with respect to each other.

2. In a switch, the combination with a base, two sets of double-angle springs secured thereon with the free upper arms of one set of springs projecting toward those of the other, and a plate underlying said arms; of two bars of insulation material slidably mounted on the base between said springs and under said plate with their adjacent faces in contact with each other, terminals extending through said bars transversely and connected with the wires which the switch is to control, and means for longitudinally adjusting said bars simultaneously and oppositely, for the purpose set forth.

3. In a switch, the combination with a base, two sets of double-angle springs secured thereon with the free upper arms of one set of springs projecting toward those of the other, and a plate underlying said arms; of two bars of insulation material slidably mounted on the base between said springs and under said plate with their adjacent faces in contact with each other, terminals extending through said bars transversely and connected with the wires which the switch is to control, a lever pivoted to said base, and links connecting said bars with points at opposite sides of the pivot of the lever, whereby movement of the latter will reciprocate the bars simultaneously and oppositely, for the purpose set forth.

In testimony whereof I affix my signature.

JOHN S. HICKMAN.
